UNITED STATES PATENT OFFICE.

JOHN TRAUM, OF COSHOCOTON, OHIO.

VULCANIZING DEVICE.

1,384,362.

Specification of Letters Patent.

Patented July 12, 1921.

Application filed March 8, 1920. Serial No. 364,240.

To all whom it may concern:

Be it known that I, JOHN TRAUM, a citizen of the United States, residing at Coshocton, in the county of Coshocton and State 5 of Ohio, have invented new and useful Improvements in Vulcanizing Devices.

The invention relates to the construction and vulcanization of casings that are used in combination with pneumatic tubes, the 10 said combination being usually referred to as the pneumatic tire. The device is an expandable sectional core, upon which the casing is constructed and vulcanized. The object of the invention is to correct certain 15 faulty conditions that are inevitable when employing a rigid core, and to eliminate the expensive and laborious method adopted in some instances to secure more favorable vulcanizing conditions than may be had with a 20 rigid core.

Note.—In the process of vulcanizing, the pressure that is applied to the forming mold that envelops the casing constructed upon a rigid core, necessarily compresses the fabric 25 or cord structure of the casing. As this compression is the result of the companion mold parts closing upon the rigid core, the conditions are favorable for the fabric or 30 cord structure of the casing to become wrinkled or bunched.

A method that is producing commendable results, is, the casing is removed from the rigid core upon which it is constructed, and there is substituted an elastic core by which 35 means the inner part of the casing is subjected to an expansive pressure during the process of vulcanizing by means of air pressure within the elastic core.

By reason of the large number of elastic 40 cores required relative to the number of finished casings produced, and additional labor required, this method adds greatly to the cost of production.

With the expandable sectional core as described in this specification I obtain a 45 greater degree of success with less labor and without the expense of providing and renewing at frequent intervals the elastic cores.

With these ends in view the invention 50 consists in the novel construction, arrangement and combination of parts hereinafter

described, illustrated in the accompanying drawings, and particularly pointed out in the appended claims.

Referring to the drawings forming a part 55 of this specification, Figure 1 is an end view of one of the sections forming the core; a section of the ring upon which the several sections of the core are mounted; and also a sectional representation of the diameter of 60 the core. Fig. 2 is a sectional representation of the core and ring on the line A A in Fig. 1, the parts controlling and operating the core being in their proper position. Fig. 3 is a perspective view of one of the expansive 65 springs. Fig. 4 is a perspective view of a spring clip and is the novel means employed to prevent the fabric or cord structure of the casing from being pressed within the opening caused by the separation of 70 the core sections when the core is expanded.

To assemble the core, the several sections forming the core are placed about the ring 5, Fig. 2 upon which they are to be mounted. The cap screws 1 are placed within the openings 75 provided for them in the ring 5, and engage the threaded openings in their respective sections of the core.

As the inner circumference of the assembled but unexpanded core is identical with 80 the outer circumference of the ring 5, by the action of the cap screws 1, the several sections of the core are securely mounted upon the ring 5. The proper alinement of the core sections is assured by means of lugs 85 and corresponding openings, 6. In this position the core is rigid and may be mounted upon the casing builder's stand (for the convenience of the casing builder the expansion springs are not placed in position until 90 the casing is to be vulcanized) and manipulated in the same manner, and with the same security as an unexpandable core.

The spring clips, Fig. 3 which are of a conformation identical to the section of the 95 diameter of the core at the contacting points of the several sections, are made to encompass the core and overlap a part of each of the companion sections.

The core in this state is ready to receive 100 the casing. The operation of the core when the casing is to be vulcanized is as follows:

Referring to Fig. 2 it will be observed that the angle and points of division of the several sections forming the core, are such as will allow the sections to be removed from the finished casing.

The pins 3, carried by the ring 5, which engage the slotted openings provided for them at the points of contact of the several sections, have a free radial movement, governed by a pin 7, (Fig. 1). The length of the pins 3, is such that their ends within the central opening of the ring 5, are of an equal distance from the circumference of the ring 5, as are the inner or head ends of the cap 10 screws 1, which secure the core sections to the ring 5; with the cap screws 2, which engage threaded openings in the ring 5, the expansion springs 4, are pivotally secured to the ring 5, and are given any desired 15 tension.

The tension of the expansion springs is attained by reason of the ring 5, serving as the fulcrum, the force of the cap screws 2, acting upon the central part of the expansion 25 springs 4, the expansive pressure of the springs is brought to bear evenly upon the cap screws 1, and the pins 3, which engage the inner circumference of the core.

In this position (as represented in Fig. 2) 30 by reason of the cap screws 1, the several sections of the core are rigidly secured to the ring 5; but, by releasing the cap screws 1 which action does not place additional pressure upon the expansion springs, but 35 does increase the space between the inner circumference of the core, and the heads of the cap screws 1, with the result that the core sections are forced from the ring 5, and are supported during the process of vulcanization of the casing by the cap screws 1, and the pins 3, which have for their 40 radial support the expansion springs 4; pivotally secured to the ring 5, by the cap screws 2.

When the core is in its expanded state 45 there is necessarily an opening at the points of separation of the sections forming the core, as these points of separation are encompassed by the spring clips, the surface 50 upon which the casing is mounted is not broken.

It may be remarked that the spring clips are made of very thin metal and that their impression upon the finished casing should 55 be so shallow as to be only faintly observed.

To remove the expansible sectional core 60 from the vulcanized casing, the expansion springs are released, the cap screws 1, are removed, which will permit the ring 5, to be removed from within the core, thus allowing the core sections to be removed in the usual manner.

Having thus described my invention without attempting to set forth all the forms in 65 which it may be made, or all the modes of

its use, I declare that what I claim and desire to secure by Letters Patent is:

1. In an expansible core the combination with sections of expansion springs adapted to impulse the sections, a continuous ring, 70 cap screws adapted to secure the sections to the ring by engaging and extending through radial openings in the ring, and engaging radial threaded openings in the inner periphery of the sections, and by their 75 proper manipulation to control the expansive action of the section, lugs and corresponding recesses in the abutting ends of companion sections adapted to correctly align the sections.

2. In an expansible core the combination with sections of expansion springs adapted to impulse the sections, a continuous ring, pins adapted to engage and extend through 80 radial openings in the continuous ring coincident with the abutting ends of companion sections and adapted to transmit the expansive force of the expansion springs to the core by contacting with slotted openings in the inner periphery and at the contacting 85 points of companion sections, pins carried by the continuous ring adapted to engage slotted recesses in the radial pins and adapted to retain and regulate the movement of the pins within the radial openings of the 90 continuous ring.

3. In an expansible core the combination of a plurality of sections, expansion springs adapted to impulse the sections, a continuous ring, radial threaded openings centrally 100 located between radial openings in the continuous ring that engage pins and cap screws respectively that transmit the expansive force of the expansion springs to the plurality of sections, openings centrally located 105 in the flat surface of the said expansion springs the said flat surface of which contact with the inner and protruding ends of the said radial pins and the said radial 110 cap screws, cap screws adapted to the said openings and engaging the said radial threaded openings in the continuous ring to secure the expansion springs and to provide pressure that reacts through the expansion springs, pins, and cap screws, to expand the core sections all as substantially 115 set forth.

4. In an expansible core the combination of a series of sections, one section having parallel ends, expansion springs adapted to 120 impulse the sections, a continuous ring, cap screws adapted to secure the expansion springs to the continuous ring, pins and cap screws carried by the continuous ring adapted to engage slotted and threaded openings 125 respectively in the inner periphery of the sections the inner and protruding ends of the said pins and the said cap screws contacting with the flat surface of the said expansion springs, means by which the core 130

members are alined and their action controlled, and metal strips adapted to conform to a portion of the surface of the core sections upon which the casing is to be constructed and vulcanized, the said properly conformed metal strips covering the points of contact of the unexpanded core sections and being of suitable width to provide a

continuous and unbroken surface to the area upon which the casing is mounted when the core sections are expanded.
